UNITED STATES PATENT OFFICE

GEORGE E. MCINTYRE, OF KANSAS CITY, MISSOURI

CARPET-SECURING DEVICE

Application filed November 30, 1928. Serial No. 322,717.

This invention relates to carpet securing devices, and more particularly to that type of carpet securing devices for use when the floor is to be completely carpeted.

The principal object of the present invention is the provision of a simple carpet securing device by means of which the carpet is secured in position without the use of tacks, clamps, or any of the usual fastening means.

Another object of this invention is the provision of a carpet securing device having an anchoring strip provided with a series of tines adapted to engage the carpet from its lower side and means for securing the strip in position.

Other objects of the present invention are simplicity and economy of construction, ease of installation, and adaptability to different building constructions.

With these general objects in view as well as minor objects which will appear during the course of the detailed specification, reference will now be made to the accompanying drawings, in which:

Figure 1, is a sectional, perspective view of a carpet securing device embodying this invention;

Fig. 2, is an enlarged perspective view of a portion of the carpet anchoring strip;

Fig. 3, is an enlarged sectional view of a building structure with the carpet securing strip in position;

Fig. 4, is a sectional view of the floor construction at the threshold showing the inner upturned flange flattened out and secured beneath the threshold plate;

Fig. 5, is a perspective view of a portion of the carpet anchoring strip with the inner flange flattened out as shown in Fig. 4;

Fig. 6, is a sectional view of the building construction with the carpet anchoring strip secured to the front side of the base board;

Fig. 7, is a fragmentary perspective view of the carpet anchoring strip as used in Fig. 6;

Fig. 8, is a sectional view showing the tines of the carpet anchoring strip positioned beneath the base shoe;

Fig. 9, is a fragmentary view of a modified

form of the carpet anchoring strip having staggered tines;

Fig. 10, is a perspective view of a modified form showing a structure similar to that shown in Fig. 3, but made of wire;

Fig. 11, is a perspective view of a modified form of the carpet anchoring strip adapted for use when no padding is used beneath the rug;

Fig. 12, is a fragmentary sectional view of a building construction showing a modified form of the carpet anchoring strip;

Fig. 13, is a perspective view of a carpet anchoring strip shown in Fig. 12.

Similar reference characters designate like parts throughout the several views and numeral 10 designates a floor, 11 a wall of any of the ordinary types, to which is secured the base board 12 in any suitable manner. 13

is a base shoe secured to the base board by means of screws for reasons hereinafter set forth. A padding 14 is preferably used beneath the carpet 15. While any carpet may be anchored by this securing device, yet it is best adapted to carpets having a nap. A carpet anchoring strip 16 made of any suitable material and provided with tines 17 adjacent one edge thereof, is shaped to fit the building structure and receive the carpet in such a

manner that the tines will penetrate the carpet 15 from its lower surface as clearly shown in figures showing the assembly. The tines are preferably inclined inwardly from the edge of the strip to prevent disengagement of the carpet therefrom. While the tines as shown are stamped from the strip,

yet it is apparent that separate tines may be swaged or otherwise secured in position on the strip 16.

Since, as shown in the drawings, a padding 14 is provided which raises the carpet above the surface of the floor, and the strip 16 is formed from thin sheet metal, it becomes necessary to raise that surface of the strip having the tines to the upper surface of the padding in order that a plane surface may be

formed for the reception of the carpet. To obtain this result the elongated body portion of carpet anchoring strip 16 is formed to produce reverse channels 18 and 19 with a

100

common inclined wall 20, an inner upturned flange 21, and an outer downturned flange 22 having its lower edge in the plane of the lower surfaces of channel 18 so that it will rest on the floor when in operative position thereon. The height of flange 22 may be varied with the thickness of the padding so as to maintain the surface of the strip 16 in a common plane with the upper surface of the padding and form a rest for the edge of the floor covering. In some cases where the base board is insecurely attached to the wall, it is necessary to attach the anchoring strip to the floor and for this purpose nail holes 23 are provided; however, nails may also be driven through the strip at any point.

Referring to Figs. 1 and 3, the installation of the preferred form of the carpet securing device will be described. With the wall and floor in place the strip 16 is positioned on the lower edge of the base board in such a manner that the upturned flange 21 will engage the inner surface of said base board. The base board is secured in position against the wall in the usual manner. The padding 14 is then placed with its outer edge butting with the flange 22. The carpet is now laid in position with its edge overlapping the strip so that as it is pressed down the tines will securely engage the body thereof to anchor it in position. The base shoe which is adapted to rest on the edge of the carpet and hold it in proper relation with the tines is now set and secured in place by suitable fastening means, such as screws. By removing the base shoe the carpet may be easily removed for cleaning.

When it is necessary to secure the carpet at places where there is no wall, for example, at the threshold, the inner flange 21 is flattened out as shown in Fig. 5, and the strip may then be secured to the floor by means of nail 24 as clearly shown in Fig. 4. The carpet may be placed in position and the threshold plate 25 secured in position as shown, with a portion of the strip and carpet extending therebeneath.

In Figs. 6 and 7, a further application of the carpet securing device which is especially adapted for use in completed building where it is not desirable to remove the base board is shown. The base shoe 13 is removed, then the strip 16' which is made narrower, is secured to the outer surface of the base, or to the floor or both by means of nails or screws passing through holes 23' formed in the strip. The tines 17' are formed adjacent one edge of the strip and the down turned flange 22' serves to level the tines with the surface of the padding 14 as in the preferred form.

Figure 8 discloses a carpet anchoring strip 16" constructed the same as the form shown in Fig. 2 with the channel 19" narrower than channel 19, thus shortening the distance from the base board to the tines 17", which are

preferably disposed vertically. The base shoe 13" when secured in position will completely cover the outer portion of the strip 16".

Fig. 9 shows the preferred form as shown in Fig. 2 with an added row of tines 26 which cooperate with tines 17 to secure the carpet in place.

The fragmentary view 10 shows a carpet securing strip formed by wire securely welded together. The cross wires 27 are formed to substantially the same shape as the cross section of the strip shown in Fig. 3, and are provided with tines 23. These cross wires are secured in position by means of longitudinal wires 29 which are formed to support wires 27 in proper position.

The simple form shown in Fig. 11 consists of a strip 30 having an upturned securing flange 31 at one edge thereof and a series of upturned tines 32 adjacent the other edge. This modified form is adapted for use when no padding is to be used beneath the rug.

Another form of carpet anchoring strip adapted for use where the carpet is laid directly on the floor is shown in Figs. 12 and 13. This strip consists of a plain strip 33 having a series of downturned tines 34 adjacent one edge thereof for securing the strip to the floor and another series of upturned tines 35 at the other edge thereof adapted to securely engage the body of a carpet to hold it in position.

While several forms of this invention have been shown to meet some of the varying conditions found in building construction, yet it is not desired to limit this invention to the forms shown, as many other modifications may be made within the scope of the appended claims without departing from the spirit thereof.

What I claim is:

1. As a new article of manufacture, a carpet anchoring strip of reverse channel form and having a series of tines adjacent one edge thereof, said tines being oppositely disposed to the adjacent channel flange.

2. As a new article of manufacture, a carpet anchoring element comprising an elongated body member having a downturned recess adjacent one edge thereof, and a series of upturned tines adjacent the other edge.

3. As a new article of manufacture a carpet anchoring strip comprising an elongated body member having an upturned flange at one edge, a downturned flange at the other edge thereof, and a series of upturned tines carried by said body member adjacent the said downturned flange.

4. As a new article of manufacture, a carpet securing device comprising an elongated body member having a raised portion at one edge thereof providing with a series of tines to engage the underside of the carpet and an upturned flange at the other edge.

thereof to be engaged by the building structure to secure the body member in place.

5. The combination with a building construction having a floor, a base board, and a base shoe, of a carpet anchoring strip extending beneath and behind said base board and having a series of tines adapted to engage the body of the carpet.

10. The combination with a building construction having a floor and a base board, of a carpet anchoring strip comprising an elongated body member having a channel thereinto to receive the lower edge of said base board, and a series of upturned tines positioned above lower edge of said base board adapted 15 to engage the carpet from its lower side.

7. The combination with a building construction having a floor, a base board and a base shoe, of a carpet anchoring strip having means whereby it is secured behind said base 20 board, and a series of tines adapted to engage the body of the carpet when the edge of the carpet is disposed beneath said base shoe.

25. The combination with a building construction having a floor, a base board, and a base shoe, of a carpet anchoring strip having an upturned flange adapted to engage the rear side of said base board, a raised portion of said strip positioned in front of said base board having a series of tines adapted to engage the carpet from its underside adjacent the outer edge of said base shoe.

30. In testimony whereof, I hereunto affix my signature.

35. GEORGE E. McINTYRE.
